FURNACE HEARTH

George E. Connolly, Oakland, Calif., assignor to
Nichols Engineering & Research Corporation,
New York, N. Y., a corporation of Delaware

Application July 20, 1940, Serial No. 346,543

2 Claims. (Cl. 263—46)

This invention relates to hearth constructions of a type particularly adapted for use in high temperature furnaces, or furnaces wherein the temperatures vary within wide limits from time to time, or vary widely at one area as compared with other areas.

The objects of the invention include the provision of an improved hearth construction which will be relatively inexpensive and simple to manufacture and install and which will be durable and capable of withstanding temperature conditions such as above mentioned over substantially longer periods of time than possible with prior furnace hearth constructions.

Various further and more specific objects, features and advantages will clearly appear from the detailed description given below taken in connection with the accompanying drawings forming a part of this specification and illustrating by way of examples, certain preferred forms of the invention. The invention consists in such novel features, arrangements and combinations, as may be shown and described in connection with the constructions herein disclosed.

In the drawings, Fig. 1 is a vertical sectional view through a portion of a furnace embodying several superposed hearths constructed in accordance with the invention;

Fig. 2 is an enlarged plan view showing a sector of one of the hearths embodying the invention;

Fig. 3 is a sectional view taken substantially along the line 3—3 of Fig. 2;

Fig. 4 is a view similar to the righthand portion of Fig. 2, but showing an alternative form of construction in accordance with the invention;

Fig. 5 is a view similar to Fig. 2 but showing a portion of another form of hearth embodying the invention; and

Fig. 6 is a sectional view taken substantially along the line 6—6 of Fig. 5.

In the example of the invention as shown in Fig. 1, a plurality of circular hearths as at 10, 11 and 12 may be superimposed to form a part of a so-called Herreshoff type of multiple hearth furnace, including a cylindrical wall as at 13 for enclosing the furnace and supporting the hearths, also including a central rotatable shaft as at 14 carrying rabble arms as at 15 having teeth cooperating with each hearth. That is, as the rabbling structure rotates, the material on hearth 10, for example, will be rabbled outwardly, whereby it will finally fall from hearth 10 through peripheral openings as at 16 on to hearth 11. At

hearth 11 the rabbling teeth are so arranged that the material will be gradually advanced toward the central area of the hearth from which it may fall through opening 18 on to hearth 12. Hearth 12 may be similar in construction and purpose, to hearth 10.

Referring now to Figs. 2 and 3, the improved construction of a typical "out" hearth such as hearth 10 will now be described. As here shown, the construction is adapted for a furnace having 10 a diameter of about 16 ft. 9 in. The hearth may be made up of a plurality of circles of refractory blocks. For example, with the particular construction shown, the blocks are arranged in six concentric circles to form the main part of the 15 hearth, the number of blocks for each circle being preferably approximately as indicated on the drawings in Fig. 3, and varying from 36 to 76. The blocks are so shaped and arranged that the upper surface 19 of the hearth, except at 20 its inner rim, will conform rather accurately to a slightly conical surface, the inclination being for example $\frac{3}{4}$ in. per twelve inches of radius, as indicated in Fig. 3. Also the blocks are so shaped that the lower surface 20 of the hearth 25 will conform to a slightly more conical surface, for example $1\frac{1}{2}$ in. per foot, as also indicated in Fig. 3. This will result in a hearth having a gradually increased thickness toward its peripheral portion, thus not only affording greater strength where the loads are most severe at the peripheral areas, but also this added thickness at the periphery will serve to protect the blocks against 30 deterioration from slagging effects caused by oil burners which are often placed beneath the peripheral portions of the hearths. Also this increased thickness will of course afford deeper areas of contact between adjacent blocks whereby the blocks may be keyed and cemented together more effectively as hereinafter explained, 35 at the peripheral areas which bear the greatest loads.

As indicated in Figs. 2 and 3, each of the blocks of the main body of the hearth is preferably 45 made relatively long and narrow, whereby all portions of each block will be relatively near the surface of the block, and thus minimizing the possibility that any portion of the refractory blocks will be underburned in the manufacture 50 thereof. Thus in order that all of the blocks of the main portion of the hearth may be in general of approximately the same weight and thickness, each succeeding circle outwardly of the hearth will embody a substantially increased num- 55

ber of blocks. The number of blocks in each circle is preferably made great enough whereby the dimension of each block in directions circumferentially of the circle, is less than the vertical dimension of the block. That is, each block in effect is positioned on edge. This has the advantage that the resistance of the tile to spalling under high temperatures is increased, for the reason that laminations due to ramming the tile molds will be along vertical confined planes instead of planes parallel to the upper and lower surfaces of the hearth. That is, the mold for each tile will normally be filled by ramming the material into the mold in a direction perpendicular to the largest surface area of the tile, with the consequence that any resulting laminations will be parallel to the plane of such surface. Hence with the tiles positioned on edge in forming the hearth, the laminations will be in vertical planes, and thus confined under pressure in each circle of blocks, preventing separation of the laminations.

The innermost circle of blocks as at 21 may have its innermost circumferential surfaces inclined upwardly and inwardly as at 22, and this circle may be adapted to receive a metal luting ring if desired as at 23, and/or a series of refractory blocks as at 24 having inclined outer faces may be provided to form the luting ring, for cooperating with suitable luting members as at 25 (Fig. 1) carried by the shaft 14, for preventing the material under treatment from falling down between the inner edge of this hearth and the rotating shaft 14.

35 The circles of blocks 26-30 inclusive as shown may all have substantially flat upper and lower surfaces and vertical side surfaces at suitable slight angles with respect to each other, whereby radially extending joints are provided between 40 abutting side surfaces of the blocks of each circle. The circumferential or end surfaces of each of these blocks, as best shown in Fig. 3, are such that succeeding joints, outwardly of the furnace, between the abutting surfaces will be at progressively increasing angles in respect to the vertical. For instance, as indicated in Fig. 3, the abutting circumferential surfaces between the blocks of circles 21 and 26 may be at an inclination (directed upwardly and outwardly 45 of the hearth) amounting to $1\frac{1}{2}$ in. per foot. Similarly, each succeeding joint outwardly of the hearth is at an increased angle such that the outer surfaces of the blocks of circle 30, for instance, are at an inclination of $2\frac{3}{4}$ in. per foot. 50 With this construction the radial dimension at the top surface of each circle will be substantially greater than the radial dimension at the bottom surface of each circle, and thus each block and each of the circles of blocks will be substantially keyed in position against the possibility that any one of the blocks or circles will slip down 55 under varying temperature conditions.

The furnace may be surrounded by an outer sheet metal cylindrical shell as at 31 preferably 60 provided with a reinforcing band as at 32 opposite each hearth. As shown in the embodiment of Figs. 2 and 3, skew blocks as at 33 may be located 65 at regions between each pair of hearth openings 16, these skew blocks having their outer surfaces 70 abutting the metallic furnace shell 31. These skew blocks may be supplemented by smaller blocks as at 34, and additional blocks of trapzoidal shape as at 35. The abutting circumferential surfaces of blocks 35, 34 and 33 respectively may 75 be at progressively increasing inclinations, as in-

dicated in Fig. 3, to provide an effective keyed relationship, as in the case of the blocks of the hearth circles. Each of the blocks 35 may be so positioned as to abut, at its inner circumferential surface, a pair of wedge-shaped blocks as at 36 forming a part of the circle 30. Each pair of the blocks 36 may alternate with a pair of oppositely directed wedge-shaped blocks as at 37. This arrangement provides a very stable and secure construction, notwithstanding the presence of the large hearth openings 16.

In constructing the furnace, after the cylindrical metallic shell of the furnace is erected, the inner wall therefor may be gradually built up with suitable insulating material or blocks as at 15 38 and refractory lining material or blocks as at 39. When the level of a hearth such as hearth 10 is reached, the skew blocks as at 33 are first cemented in place. A suitable removable frame for supporting the hearth during its construction 20 may be put in place and the blocks such as at 34 and 35 are then put in place with joints to adjacent blocks cemented. The blocks as at 36, 37 of the outermost circle 30 are then put in place and the last of these blocks to be inserted, for example one of the blocks 37, may be formed with side surfaces slightly wedge-shaped, whereby when the block is driven downwardly toward the temporary hearth supporting frame, it will be wedged into position and tend to expand the 30 circle 30 somewhat, into firm engagement with the blocks 35 and with the blocks 36, 37 firmly engaging each other. Thereafter each of the succeeding circles of blocks 29, 28, etc., may be similarly put in place one after another, the final block of each circle being driven or wedged into position so that each circle will be firmly keyed to the succeeding outer circle.

The side surfaces of all of the blocks may be cemented together, with a suitable high temperature resistant-bonding cement, except that along certain lines such as line 40 dividing the hearths into sections or quadrants, the cement may be omitted, this in effect permanently dividing the hearth into sections or sectors. To prevent 45 cement from getting into the joints of these lines of separation, thin strips of paper may be inserted as along the line 40 during assembly of the hearth. With the hearth thus effectively divided into sections, in the event one section is 50 expanded or contracts more than others, then a slight movement of one section with respect to the others is possible, without danger of irregular cracking of various blocks or joints between blocks. Instead, each section of the hearth is 55 free for slight movement in respect to adjacent sections along definite predetermined lines preferably continuous and radial, and in such a manner as to not injure the blocks. This feature is of substantial importance in cases such as where fuel 60 burners may be arranged at widely spaced positions around the periphery of the hearth, thus causing uneven heating thereof, or in cases where burners may be applied to one edge of the hearth while burners at the opposite edge are extinguished.

At various places around the wall of the furnace between each pair of hearths, inspection openings may be provided through the furnace wall, the dotted lines at 41 indicating the limits 70 of one such opening.

In erecting the steel furnace shell, especially for large furnaces, it may be difficult to so install the same that its diameter will be uniform as distinguished from being only roughly 75

uniform from place to place. Hence if the skew-back blocks as at 33 were all of uniform dimensions and were placed in contact with the inner surface of such shell, difficulties would be encountered in locating all of the hearth circles in truly concentric relationship, as desired with respect to the central shaft of the furnace. To avoid these difficulties, where the furnace shell is of only approximately uniform diameter, the skew-back blocks as at 33' of Fig. 4 may be made somewhat smaller in their radial dimension, whereby space as at 42 is provided between the outer circumferential surfaces of these blocks and the interior of the furnace shell. With this construction all of the skew-back blocks 33' may be put in place at a uniform distance from the center of the furnace and the spaces 42 may be thereafter filled in with Portland cement grout.

The construction of a typical "in" hearth such as hearth 11, is shown in Figs. 5 and 6 and may comprise for example five concentric circles of blocks, the outermost of which engages a circle of skew-back blocks mounted within the furnace wall. The construction and arrangement of the inner circles 26'-30' as shown in these figures will be understood from the above explanation of the construction of these circles 26-29 of Fig. 2, as above described. In the circle of skew blocks of Fig. 5, blocks such as at 43 may stop short of the furnace shell 31 as shown, and the intervening space 42' may be filled with cement grout as in Fig. 4. However, skew-back blocks as at 44 and 45 which are located above or below a wall opening as at 41' are preferably cut on the job so as to substantially accurately fit the inside surface of the furnace shell without the intervening layer of cement. As shown in Fig. 5, one of the dry joints without cement, for dividing the hearth 40 into sections, may be provided along the line 40'.

Where multiple hearth furnaces of the above indicated type are operated constantly and continuously over long periods of time at temperatures which are not exceedingly high, and so that the hearths are not subjected to wide temperature variations, not much difficulty is encountered with hearth constructions of types heretofore known. However, when such furnaces are used for example, for the calcining of lime at temperatures in the neighborhood of 1800° F. and where the furnace is operated at intervals with frequent shut-down periods, the resulting expansion and contraction of the

hearts tends to cause serious cracking or slipping of blocks and resulting general deterioration of prior known hearth constructions. However, with the above described constructions, these difficulties may be effectively eliminated.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. A hearth construction for high temperature furnaces, comprising refractory blocks shaped and arranged to form a circular hearth with a slightly conical upper surface and a somewhat more conical lower surface, and an annular series of skew-back blocks surrounding the hearth and embraced by a cylindrical metallic furnace wall, the hearth areas including a plurality of concentric rings formed of the blocks, the blocks of each ring being wedged in a circumferential direction to expand the ring and maintain same under pressure against the next outer ring, the blocks being shaped to provide between adjacent rings, abutting surfaces which at succeeding rings outwardly of the hearth are at progressively increasing angles to the vertical, whereby the circumferential surfaces of the blocks of each ring are keyed in respect to the next inner and outer rings.

2. A hearth construction for high temperature furnaces, comprising in combination, refractory blocks shaped and arranged to form a circular hearth with self-supporting central arch areas including a plurality of concentric rings of blocks, the hearth being formed with a plurality of drop-holes around its periphery, skew-back blocks between said openings for supporting the hearth, and the outermost of said rings of blocks including at areas between each pair of adjacent holes, a plurality of wedge-shaped blocks directed toward the center of the hearth and maintained by the skew-back blocks under pressure in a direction tending to wedge apart the blocks of said outermost ring, so as to tend to expand the ring.

GEORGE E. CONNOLLY.
